UNITED STATES PATENT OFFICE.

ARTHUR A. KRAEUTER, OF SOUTH ORANGE, NEW JERSEY.

DESIGN FOR AN ORNAMENTATION OF A PLIER-HANDLE.

59,602.

Specification for Design.

Patented Nov. 8, 1921.

Application filed April 8, 1920. Serial No. 372,360. Term of patent 14 years.

To all whom it may concern:

Be it known that I, ARTHUR A. KRAEUTER, a citizen of the United States, residing at South Orange, in the county of Essex and State of New Jersey, have invented a new, original, and ornamental Design for Ornamentation of Plier-Handles, of which the following is a specification, reference being made to the accompanying drawings, forming part thereof.

In the drawings Figure 1 is a plan view, and Fig. 2 is a side view of a pair of pliers embodying my design.

I claim:

The ornamental design for an ornamentation of a plier handle as shown.

ARTHUR A. KRAEUTER.
